UNITED STATES PATENT OFFICE

EMIL C. RITTER, OF RAHWAY, NEW JERSEY, ASSIGNOR TO F. A. D. ANDREA, INC., OF NEW YORK, N. Y., A CORPORATION OF NEW YORK

DESIGN FOR A RADIO RECEIVING APPARATUS CABINET

Application filed August 7, 1930. Serial No. 36,591. Term of patent 3½ years.

To all whom it may concern:

Be it known that I, EMIL C. RITTER, a citizen of the United States, and resident of Rahway, in the county of Union, and State of New Jersey, have invented a new, original, and ornamental Design for Radio Receiving Apparatus Cabinets, of which the following is a specification, reference being had to the accompanying drawing forming part thereof.

Fig. 1 of the drawing is a perspective view of the radio receiving apparatus cabinet, showing my new design.

Fig. 2 is a plan view of the cabinet shown in Fig. 1.

Fig. 3 shows an elevation of a portion of the cabinet, located behind the pair of doors shown in Fig. 1.

I claim:—

The ornamental design for a radio receiving apparatus cabinet as shown, and described.

Signed at New York, in the county of Queens, and State of New York, this 25th day of July, A. D. 1930.

EMIL C. RITTER.
